UNITED STATES PATENT OFFICE.

JAMES E. LAPPEN, OF LE ROY, MINNESOTA, ASSIGNEE TO UNION FIBRE COMPANY, OF WINONA, MINNESOTA, A CORPORATION OF MINNESOTA.

MACHINE FOR MANUFACTURING HEAT-INSULATING SHEETS FROM FLAX FIBER.

1,056,915.

Specification of Letters Patent. Patented Mar. 25, 1913.

Application filed March 11, 1910. Serial No. 548,743.

To all whom it may concern:

Be it known that I, JAMES E. LAPPEN, a citizen of the United States, residing at Le Roy, in the county of Mower, State of Minnesota, have invented certain new and useful Improvements in Machines for Manufacturing Heat-Insulating Sheets from Flax Fiber; and I do hereby declare the following to be a full, clear, and exact description of the same, reference being had to the accompanying drawings, forming a part of this specification, and to the figures and letters of reference marked thereon.

This invention relates to apparatus for producing sheets of fiber for heat insulating purposes, the objects of the invention being to provide a machine which will effectually handle and distribute the fiber in such manner as to produce an even distribution and a proper entanglement and adhesion of the fibers with each other in the completed sheet or board and to perform the necessary steps in a continuous succession, whereby sheets or boards of an indeterminate length may be produced.

The invention consists in certain novel details of construction and combination and arrangements of parts, all as will be herein-after described and pointed out in the appended claims.

Referring to the accompanying drawings—Figure 1 is a longitudinal section through a machine embodying the present improvements, portions being broken away and portions of the driving mechanism omitted. Fig. 2 is a vertical section through a portion of the machine to show particularly the submerging roll and tension roll for the conveyer belt on which the fiber is distributed and given preliminary form. Figs. 3 and 4 are detail sections in vertical and horizontal planes, respectively, through one of the tampers. Fig. 5 is a fragmentary section of the conveyer belt on which the fiber is distributed and formed, and Fig. 6 is a vertical section with parts broken away and in elevation, of the foraminous cylinder upon which the fiber is delivered from the forming conveyer.

Like letters of reference in the several figures indicate the same parts.

The machine of the present invention is designed especially to handle flax fiber and embodies in its construction a central relatively long tank A preferably with its bot-

tom walls converging to a sediment discharge A' and having a suitable water inlet A² and an overflow outlet, the height of which may be controlled by an adjustable gate A³, whereby the depth of water in the tank may be regulated. Running on suitable rollers B, located in proximity to opposite ends of the tank, and with their upper surfaces above the water level, is a continuous conveyer usually formed by side chains b, (Fig. 5), and transverse slats b', the arrangement being such that the ends of the conveyer are somewhat above the water level and the discharge end higher than the entrance end, while the intermediate portions of the belt dips below the water level to a greater or less depth as required by the conditions of the fiber being handled or the thickness of the sheet or board to be formed. The intermediate portion of the top reach of the conveyer is preferably kept submerged by a submerging roller C, suitably journaled in the side walls of the tank and preferably having on one end of its shaft a sprocket wheel C', Fig. 2, whereby it may be driven, the said roller, if desired, being driven by a sprocket chain which also serves to impart movement to the conveyer belt. The tension of the conveyer belt is maintained by a tension roller c, preferably engaging the inner surface of the lower reach of the belt below the roller C and held downwardly to give the desired tension by any ordinary belt tightening means, such, for instance, as an adjustable or weighted lever of well known construction. To limit the submergence of the intermediate portion of the upper reach of the conveyer belt and to properly support the same against the pressure exerted by the roller C and the tampers to be hereinafter described, a series of rollers c', c², c³, c⁴, c⁵, c⁶ are preferably journaled in the walls of the tank and extend across beneath the upper reach of the conveyer, each in position to receive and support the conveyer and to prevent downwardly deflection of the same by the action of the roller C and tampers.

On each side of the roller C are vertically movable reciprocatory tampers D, shown in detail in Figs. 3 and 4, and preferably each composed of a series of wooden boxes or blocks d which may be spaced apart or have their operative faces rounded as shown in Fig. 4, and a bar or blade d' with

its forward face inclined at an angle with respect to the box or blocks d , whereby the action of the tampers on the fiber will be to force the fibers forward through the pressure of the boxes or blocks d , at the same time such forward movement is retarded or the fiber moved rearwardly by the action of the lip of the blade d' , with the result that the fiber is more evenly distributed over the conveyor and voids or thin places filled. The tampers D and roller C are located immediately above the first three rollers c' , c^2 , c^3 , respectively, and above the roller c^4 there is arranged another tamper D' , the lower or operative face of which is preferably rounded and, as the conveyor is, at this point, arranged to emerge from the water in the tank, the tamper D' operates to press out or remove a part of the water and smooth down the fiber on the conveyor. Above the rolls c^5 , c^6 , are still other tampers d^2 , d^3 , preferably having oppositely inclined operative faces converging to rounded edges and said tampers operate to still further smooth up and even the fiber sheet or board with respect to its thickness. All the tampers may be conveniently mounted on the lower ends of vertical carriers E , which, at their upper ends, are hung on suitably driven eccentrics E' and the eccentrics may be driven by sprocket chains e or other suitable connections with a prime mover.

For distributing the fiber to the conveyor belt on which it is formed into a sheet or board there is provided a fiber elevating and doffing mechanism preferably substantially as follows: At the entrance end of the machine a hopper F is provided for the reception of the bulk of fiber, said hopper having an inclined bottom or wall f down which the fiber will gravitate into contact with a toothed elevating conveying belt G forming one wall of the hopper and guided on rollers G' at top and bottom of the elevator. At an intermediate point in the length of the belt there is provided a rotary retarding doffer H having arms h adapted to run in proximity to the teeth of the elevator, but in a reverse direction, so as to break up and return to the hopper excess fiber or fiber which might be carried up in bunches or lumps. The fiber is discharged from the upper end of the elevator through a hood I onto the end of the forming conveyor before it reaches the first tamper D and, to assist the discharge of the fiber from the elevator and to distribute the same in a light flocculent condition, a second doffer H' is provided in the hood I . The arms h' of this doffer move in the same direction as the teeth of the elevator but at a higher speed to thereby take the fiber from the elevator and distribute it in such manner that it will settle down upon the forming conveyor in a substantially uniform mat which is con-

tinually being carried off by the forming conveyor, tamped down and formed into shape by the tampers and rolls before described. To give shape to the edges of the sheet or board the roll C , before referred to, is preferably provided with end flanges C^2 (Fig. 2) said flanges also serving the important function of maintaining the forming conveyor in proper alignment. In proximity to the discharge end of the tank the forming conveyor runs between pressure rolls K , K' the upper roll K being preferably of relatively large diameter and supported in adjustable spring pressed bearings of ordinary construction, said rolls operate to still further smooth and compress the fiber to the desired thickness and also to squeeze excess water from the fiber. From the forming conveyor the fiber may pass over a small intermediate roller k to the upper surface of a large foraminous drum L where remaining water may drain away through the peripheral covering of the drum and in the preferred arrangement the action is assisted by a weighted roller M bearing on the drum at a point in proximity to the point where the fiber leaves the same, said weighted roller being itself supported in a frame or hanger M' hinged at m to the frame of the machine.

The foraminous drum L is located immediately adjacent the discharge end of the tank and in position to receive the discharge over the gate A^3 , whereby not only is the foraminous periphery of the drum washed, but such particles of fiber as may be floating in the water are deposited on the periphery of the drum and thereby carried up into contact with the under surface of the sheet or board to which they will adhere and be carried off of the same. From the foraminous drum L the sheet or board of fiber is led off over intermediate supports N and between pairs of pressure rolls O , O' . The pressure rolls are adjustable so as to compress the felt or sheet to the desired degree before it is delivered to the finishing apron indicated at O^2 . The arrangement of the rollers is such that the felt or sheet may be delivered to the finished apron in practically any condition of dampness desired and the fibers will, by the action of the several parts of the machine, be so interlaced and compacted that the sheet is very coherent and may be handled without difficulty.

The pressure roll M , before referred to, is mounted so that it may be conveniently swung upwardly to permit of the fiber, bat, or sheet being led from the foraminous drum to the pressure rolls in starting the machine.

For effective adjustment the tampers are preferably adjustably supported or connected with their operating eccentrics so that they may be made to strike with greater

or less pressure on the body of fiber passing on the forming conveyer.

There is arranged below the foraminous drum a suitable water collector and discharge P and below the tank A there is arranged a chamber Q in position to receive the discharge from the sediment valve A', said chamber Q itself having an outlet opening adapted to be closed by a suitable valve 10 or door Q'. By arranging a chamber Q in the position indicated, the continued operation of the machine need not be interrupted in order to discharge sediment from the tank inasmuch as the sediment may be allowed 15 to run out of the tank into the chamber, and after the sediment valve A' is closed the chamber itself may be emptied and the sediment collected therefrom.

Obviously, any suitable prime mover may 20 be employed for driving the several parts of the machine, but if the parts are arranged as shown I prefer to employ three separate motors, such as electric motors, one for driving the elevator and one of the doffers 25 while a second motor drives the tampers whereby they may be operated fast or slow, regardless of the rate of operation of the remaining portion of the machine. The third motor drives the forming conveyer, sub- 30 merging and pressure roll C, foraminous drum and pressure rolls O—O'. The roll K need not be a driven roll and the same is true of the pressure roll M running on the foraminous drum, although it is understood 35 that these rolls may be driven if desired. The arrangement of three separate motors is simply a convenient arrangement which will be readily understood without illustration for permitting the feeding mechanism, 40 the conveying belt, etc., and the tampers to be driven at different relative speeds so as to vary the character of the product, but it is obvious that differential gearing of well known character may be employed for 45 this purpose in lieu of separate motors.

In operation water is supplied continuously to the tank and the matting and initial compression of the fiber takes place under water, this being a highly important feature, especially in operating on flax fiber.

Having thus described my invention, what I claim as new and desire to secure by Letters Patent of the United States, is:

1. In a fiber board or felt forming machine, the combination with a tank adapted to contain liquid, of an endless slatted conveyer mounted on supports to travel from a point above the liquid to a point below the liquid and thence to a point above the liquid, means above the water and conveyer for distributing fiber on the conveyer in proximity to one end of the tank and means for removing the sheet of fiber in proximity to the opposite end of the tank, substantially 65 as described.

2. In a fiber board or felt forming machine, the combination with a tank adapted to contain liquid, of an endless slatted conveyer exposed for the reception of fiber at a point above the liquid, tampers, and a 70 submerging roll operating on the top of the fiber and conveyer to press the same below the surface of the liquid at a point intermediate the length of the conveyer and means for lifting the conveyer and fiber above the liquid as they approach the discharge end, substantially as described.

3. In a fiber board forming machine, the combination with a vessel adapted to contain liquid, of an endless slatted conveyer 80 adapted to receive the fiber at a point above the liquid and a submerging roll depressing the conveyer and fiber below the surface of the liquid at a point intermediate the length of the conveyer, of reciprocatory tampers 85 having irregular operating faces for distributing the fiber to fill holes that may occur in the fiber board or felt, substantially as described.

4. In a fiber board or felt forming machine, the combination with a vessel adapted to contain liquid, of an endless slatted conveyer, pressure rolls, a perforated cylinder for transferring the fiber board from the conveyer to the pressure rolls, and a 90 roller acting on the fiber board or felt on the perforated cylinder for removing part of the water and preventing the fiber board or felt from being pushed back from the pressure rolls, substantially as described. 100

5. In a fiber board or felt forming machine, the combination with a vessel adapted to contain liquid, an endless slatted conveyer therein, a perforated cylinder adapted to receive the fiber board from the conveyer, 105 of an overflow discharge for the vessel in position to direct the water against and through the perforated cylinder whereby the fine particles of fiber carried off by the water are deposited on the cylinder and carried thereby into contact with its fiber board.

6. In a fiber board or felt forming machine of the type described, a toothed cylinder to distribute the stock, tampers acting 115 directly on the stock carried by the conveyer to felt and condense the same, a slatted conveyer for receiving the distributed stock, and means for keeping an intermediate portion of the conveyer submerged to wet the 120 stock.

7. In a fiber board or felt forming machine, the combination with a tank, an endless conveyer therein and guiding supports for supporting both the receiving and discharge ends of the conveyer above the water level in the tank, of means for distributing fiber on the receiving end of the conveyer above the water level, tampers acting 125 directly on the stock carried by the conveyer 130

- veyer to felt and condense the same, and means near the receiving end of the conveyer for depressing and submerging the conveyer and fiber being carried on the 5 conveyer toward the discharge end.
8. In a fiber board or felt forming machine, the combination with a tank, an end- 55 less conveyer therein, guiding supports for supporting the discharge end of the conveyer above the water level in the tank, and means for distributing fiber on the conveyer in proximity to the end thereof opposite the discharge end, of a tamper and roller coöperating directly with the fiber on the 60 conveyer for depressing and submerging the fiber at a point intermediate the ends of the conveyer and tampers coöperating directly with the fiber on the conveyer for distributing, evening and press- 65 by the conveyer.
9. In a fiber board or felt forming machine, the combination with a tank, an end- 70 less conveyer therein, rotary supports for opposite ends of said conveyer having their upper surfaces above the water level, an intermediate roller located above the upper reach of the conveyer for coöperating with 75 the fiber on the conveyer to submerge the same at a point intermediate the ends of the conveyer, and a plurality of reciprocatory tampers coöperating with the fiber on the conveyer to even, distribute, and press the same during the forward movement of the 80 conveyer.
10. In a fiber board or felt forming machine, the combination with a tank, an end- 85 less conveyer therein, supports for opposite ends of the conveyer, a roller above the upper reach of the conveyer intermediate the ends of the same and having its lower surface below the water level in the tank, reciprocatory tampers located above the upper 90 reach of the conveyer, and supports for the upper reach of the conveyer located below the tampers, substantially as described.
11. In a fiber board or felt forming machine, the combination with a tank, an end- 95 less conveyer therein, means for distributing fiber to one end of said conveyer, a foraminous drum for receiving the fiber from the opposite end of the conveyer, and an over- 55 flow opening for the tank discharging on the foraminous drum below the point where the fiber from the conveyer is supported thereby, whereby fiber from both the tank discharge and from the conveyer will be deposited on the foraminous drum, and a water supply for the tank, substantially as 60 described.
12. In a machine of the kind described, the combination with a water containing tank, of an endless conveyer apron operative to carry the stock from a point below to a 65 point above the water, and a multiplicity of tampers working above said conveyer and operative successively on the stock to progressively reduce the thickness of the fibrous sheet, the fiber engaging edges of said tampers being inclined to the surface of the stock. 70
13. In a machine of the kind described, the combination with a water containing tank and an endless open apron operative to carry the stock from a point below to a point 75 above the water, rollers overlying the belt at a point below and at a point above the water level, respectively, and tampers operative on the stock carried by the apron between the rollers. 80
14. In a machine of the kind described, the combination with a water containing tank, of an endless apron operative to carry the stock from a point below to a point above the water, and a multiplicity of tampers working above said apron and operative successively on the fibrous stock to progressively reduce the thickness of the fibrous sheet. 85
15. In a machine of the kind described, the combination with a water containing tank, of an endless apron operative to carry the fibrous stock from a point below to a point above the water, of a tamper operative above said belt and having its stock engaging lower edge beveled backward in respect to the direction of the travel of the stock on said belt, whereby surplus stock will be crowded backward. 90
